US00D752742S

(12) **United States Design Patent**
Oberg et al.

(10) **Patent No.:** **US D752,742 S**
(45) **Date of Patent:** **** Mar. 29, 2016**

(54) **NEEDLE GUIDE MOUNTING FIXTURE**

(71) Applicant: **C. R. Bard, Inc.**, Murray Hill, NJ (US)

(72) Inventors: **Kevin M. Oberg**, Clinton, MS (US);
Jonathan C. Gorzitz, Kaysville, UT (US)

(73) Assignee: **C. R. Bard, Inc.**, Murry Hill, NJ (US)

(**) Term: **14 Years**

(21) Appl. No.: **29/493,146**

(22) Filed: **Jun. 5, 2014**

Related U.S. Application Data

(60) Continuation-in-part of application No. 13/886,196, filed on May 2, 2013, which is a division of application No. 12/642,456, filed on Dec. 18, 2009, now Pat. No. 8,574,160.

(57) **CLAIM**

The ornamental design for a needle guide mounting fixture, as shown and described.

DESCRIPTION

FIG. 1 is a front perspective view of a first embodiment of a needle guide mounting fixture;

FIG. 2 is a rear perspective view of the needle guide mounting fixture of FIG. 1;

FIG. 3 is a side elevation view of the needle guide mounting fixture of FIG. 1;

FIG. 4 is a top plan view of the needle guide mounting fixture of FIG. 1;

FIG. 5 is a front elevation view of the needle guide mounting fixture of FIG. 1;

FIG. 6 is a rear elevation view of the needle guide mounting fixture of FIG. 1;

FIG. 7 is a front perspective view of a second embodiment of a needle guide mounting fixture;

FIG. 8 is a rear perspective view of the needle guide mounting fixture of FIG. 7;

FIG. 9 is a side elevation view of the needle guide mounting fixture of FIG. 7;

FIG. 10 is a top plan view of the needle guide mounting fixture of FIG. 7;

FIG. 11 is a front elevation view of the needle guide mounting fixture of FIG. 7; and,

FIG. 12 is a rear elevation view of the needle guide mounting fixture of FIG. 7.

The broken lines immediately adjacent the shaded areas represent the bounds of the claimed design while all other broken lines are directed to environment; the broken lines form no part of the claimed design.

1 Claim, 8 Drawing Sheets
